United States Patent Office

Des. 194,313
Patented Jan. 1, 1963

194,313

RAILING

Robert H. Murdock, 203 Willamette St.,
Kensington, Calif.

Filed July 10, 1961, Ser. No. 65,858

Term of patent 14 years

(Cl. D13—7)

FIG. 1

FIG. 2

FIG. 3

FIG. 4

FIG. 5

FIGURE 1 is a front elevational view of a railing showing my new design;

FIGURE 2 is a side elevational view thereof;

FIGURE 3 is a top plan view thereof;

FIGURE 4 is a rear elevational view thereof;

FIGURE 5 is a view of the underside of the railing.

I claim:

The ornamental design for a railing, as shown.
